(57) **CLAIM**

I claim the ornamental design for a spout lid with handle, as shown and described.

DESCRIPTION

FIG. 1 is a Perspective view of a spout lid with handle showing my new design, showing the handle feature in a horizontal position of use and showing the spout lid in an open position of use;

FIG. 2 is a Front view thereof;

FIG. 3 is a Back view thereof;

FIG. 4 is a Right-side view thereof;

FIG. 5 is a Top view thereof;

FIG. 6 is a Bottom view thereof;

FIG. 7 is another perspective view thereof; showing the handle feature in a vertical position of use and showing the spout lid in a closed position of use; and,

FIG. 8 is another perspective view of a spout lid with handle, showing the handle feature in a horizontal position of use. The broken lines are for the purpose of illustrating portions of the article that form no part of the claim.

1 Claim, 8 Drawing Sheets
